H. P. MARSHALL & G. E. DANIELS,
DISH WASHING MACHINE,
APPLICATION FILED JAN. 8, 1915.

1,152,532.

Patented Sept. 7, 1915.

UNITED STATES PATENT OFFICE.

HOWARD P. MARSHALL AND GEORGE E. DANIELS, OF DAYTON, OHIO.

DISH-WASHING MACHINE.

1,152,532.

Specification of Letters Patent.

Patented Sept. 7, 1915.

Application filed January 8, 1915. Serial No. 1,086.

To all whom it may concern:

Be it known that we, HOWARD P. MARSHALL and GEORGE E. DANIELS, citizens of the United States, residing at Dayton, in the 5 county of Montgomery and State of Ohio, have invented certain new and useful Improvements in Dish-Washing Machines; and we do declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

This invention relates to new and useful improvements in dish washing machines.

The object of the invention is to provide a machine of this kind which is especially 20 available for household use and of simple construction and efficient.

A further object of the invention is to provide such a machine with a supporting frame of a form which enables said machine to be 25 moved to and supported over a kitchen sink when it is desired to use it, and removed therefrom when the work of washing the dishes is finished.

With the foregoing general objects in 30 view, reference is made to the accompanying drawings of which—

Figure 1 is a front elevation of the machine with parts of the cylinder door broken away to reveal structural parts; and Fig. 2 35 is a side elevation thereof with parts of the end of the cylinder broken away; and Fig. 3 is a detail view of one of the seals between the lid and the cylinder.

In a detail description of the invention, 40 similar reference characters indicate corresponding parts in both the drawings and the description.

The frame is especially designed to support the washing machine in a convenient 45 manner over the kitchen sink. To this end it consists of two overhanging side frame members 1 which, by reason of their overhanging character, enable the frame to be moved up to the sink, shown in dotted lines, 50 to a position to bring the washing machine entirely over the sink, the latter being shown in dotted lines, Fig. 2. The lower ends of the frame members 1 extend in a frame consisting of four legs 2 which are joined by 55 cross members 3 and 4, the former being curved extensions which radiate from the

frame member 1. Between the frame members 3, a brace bar 5 extends and between the members 4 two such brace bars 6 extend. The entire frame so constructed enables the 60 overhanging members 1 to rise from one side thereof. The supporting frame so constructed is supported on casters 7 which enable it to be conveniently moved around to and from the sink or other places. The upper ends of the 65 overhanging frame members 1 are provided with apertured bosses 1' which provide bearings for the two stub shafts 7 and 8 through which the washing machine is rotated. The washing machine consists of a cylinder 9 70 which has inclosing heads 9' and a cover 10, the latter being united to a series of straps 11 which are hinged at one end thereof to hinge pieces 12 secured to said cylinder. The other end of each of said lid straps 11 is 75 provided with a dog or latch 13 which cooperates with a pin 14 to maintain the cover closed when the machine is in operation. The pins 14 are secured to bifurcated blocks 14' which are secured to the cylinder. The 80 opening or mouth of the cylinder is provided with sealing strips 15 and 16 two of which are fixed to the outer side of the cylinder along the edges of the opening, and the other two of which are fixed to the inner 85 side of the cover. As seen from Fig. 2, the strip 15 at the top is attached to the cover and the strip 16 is attached to the cylinder, while at the bottom the strip 16 is attached to the cover and the strip 15 is attached to 90 the cylinder. The adjacent surfaces of said sealing strips 15 and 16 are tapered throughout their lengths to provide a snug fit between them and to thus, in connection with other elements to be presently described, 95 form an efficient seal to prevent leakage from the cylinder. A corrugated metal strip 15' is secured to the outer side of the sealing strip 15 at the bottom to cushion the impact of the door. One head of the cylinder is 100 fixed to the stub shaft 7 so that both cylinder and shaft rotate together, while the shaft 8 at the other end of said cylinder is stationary and the cylinder rotates thereon. The interior of the cylinder and the cover 105 therefor is provided with a series of stirrers 17 fixed thereto and extending longitudinally thereof. Two of these stirrer blades, to-wit, 17', are fixed to the inner side of the cover 11 in positions so that they will enter 110 the cylinder at the margins of the opening. The margins of the opening in the cylinder

- are turned inwardly as at 18 and abut with the stirrer blades 17' and these, together with the sealing strips 15 and 16 effectually seal the opening when the cover is closed. 55
- 5 The stirrer blades 17 have each a clearance between them and the inner sides of the cylinder and cover which provide openings 19 through which the water passes and circulates when the cylinder is rotated. 60
- 10 The dish container consists of a wire basket 20, the ends and sides of which are suitably strengthened by the use of larger wire in its construction, the ends terminating in convenient forms of bail or handles 21. A portion of the said dish basket may be provided with slanting wire partitions 22 between which flat dishes, such as plates, and saucers, may be placed in position which permit the water to come in contact with both sides 65 thereof. The said wire basket is supported in suitable end frames 23 which have inwardly projecting lugs at three or more points 24 between which the basket is secured. A baffle blade 25 projects downwardly from said frames 23 below the basket and interposes a barrier at that point to the flow of the water and throws it up into the basket from the bottom of the cylinder as the latter is rotated. This effect occurs when each of the stirrers 17 and 17' arrive in line with said baffle blade, as seen in Fig. 2. One of the basket frames or brackets 23 is suspended from the shaft 7, the connection being loose in order to permit said 70 shaft to rotate, while the other of said frames 23 is fixed in a similar position to the shaft 8 by a screw 26. A suitable drain opening in the cylinder is closed by a screw-cap 27 and said cylinder may be locked 75 against rotation when not in use by means of a sliding pin 28 adapted to enter a socket piece 29 on an end thereof. The cylinder is rotated by means of a crank 30 which is pinned to the stub shaft 7. 80
- 45 Having described our invention, we claim.
1. In a dish washing machine, the combination with a rotatable cylinder, a cover hinged thereto, a series of stirrer blades fixed to the interior of said cylinder and 85 cover, a dish receptacle in said cylinder, brackets in which said receptacle is support-
- ed, and a baffle blade supported in said brackets in a position to align with said stirrer blades during the rotation of the cylinder, substantially as described. 90
2. In a dish washing machine, the combination of a cylinder, a door hinged to said cylinder, a series of stirrer blades fixed to the inner sides of said cylinder and cover, inwardly projecting flanges at the margins 95 of the opening in the cylinder, the stirrer blades at the edges of the cover being adapted to engage said inwardly projecting flanges, and strips on the cylinder and cover respectively coöperating with said stirrer blades in sealing the opening in the cylinder, substantially as described. 100
3. In a dish washing machine, the combination of a cylinder and a cover, said cylinder having inturned marginal flanges at the opening thereof, a series of stirrer blades arranged on the inner sides of said cylinder and cover, two of said stirrer blades on the cover being in positions to engage said inturned marginal flanges, sealing strips on the cover abutting with said two stirrer blades, and sealing strips on the cylinder engaged by the sealing strips on the cover, said sealing strips on the cylinder and cover and the stirrer blades and flanges coöperating to effectually seal the opening in said cylinder. 105
4. In a washing machine, the combination with a rotatable cylinder having a cover, and a series of stirrer blades arranged on the inner sides of said cylinder and cover, having water passages between them and the adjacent surfaces of the cylinder and cover of a dish basket in said cylinder, end brackets in which said basket is supported, and a baffle 110 blade projecting from the lower ends of said brackets and adapted to throw the water into the basket when the stirrer approaches said baffle blade. 115
